EDWARD KENER, JR., OF BUFFALO, NEW YORK.

REFUSE-INCINERATOR.

1,194,506.

Specification of Letters Patent. Patented Aug. 15, 1916.

Application filed March 23, 1914. Serial No. 826,613.

To all whom it may concern:

Be it known that I, EDWARD KENER, Jr., a citizen of the United States, residing at Buffalo, in the county of Erie and State of New York, have invented new and useful Improvements in Refuse-Incinerators, of which the following is a specification.

This invention relates to an incinerator or a crematory which is more particularly designed for burning or destroying garbage or refuse from the kitchens of households, restaurants, hotels, hospitals, etc., so as to avoid dangers of sickness and unpleasant odors and also dispose of such matter in a sanitary manner.

One of the objects of this invention is to produce an incinerator or crematory of this character which will thoroughly and quickly consume and reduce to ashes the various kinds of garbage or refuse derived from kitchens regardless of how wet the same may be without liability of clogging the apparatus and to accomplish this in such manner that the gases developed during the drying and burning of the refuse will aid materially in the reduction to ashes of the refuse under treatment, so that comparatively little fuel is required for this purpose.

Another object of my invention is to provide an apparatus of this character which is so constructed that the same will not unduly heat the room or space immediately surrounding the apparatus.

Further objects of this invention are to provide improved means for automatically opening and closing in unison the fuel supply valve and the draft door of the ash pit and to provide improved means for locking the fuel valve in its opened or closed position.

In the accompanying drawings: Figure 1 is a front elevation, partly in section, of a refuse incinerator embodying my improvements. Figs. 2 and 3 are horizontal sections taken in the correspondingly numbered lines in Fig. 1. Fig. 4 is a vertical longitudinal section taken in line 4—4, Fig. 1. Fig. 5 is a fragmentary sectional perspective view of my improved incinerator. Fig. 6 is a fragmentary horizontal section of the refuse receptacle and the by-pass flue showing the manner of assembling the same. Fig. 7 is a fragmentary vertical section, on an enlarged scale, taken in line 7—7, Fig. 1 and showing

the means for opening and closing the air door and fuel valve simultaneously and the means for locking the valve in its open or closed position. Fig. 8 is a top plan view thereof.

Similar characters of reference indicate corresponding parts throughout the several views.

1 represents the hollow base of the incinerator which is preferably supported on the floor by legs 2 to permit air to reach the underside of the base.

28 represents the door or lid which controls an opening in the front side of the ash pit for permitting the removal of the ashes from this pit and also to admit air to the burners and the material under treatment. This door is preferably pivoted on the outer side of the apparatus at its upper end so as to swing vertically. Above this base is arranged the ash pit or box 3 which receives the ashes resulting from the combustion of the garbage or refuse and above the ash pit is arranged the receptacle or compartment 4 which receives the refuse or garbage to be cremated. Above the refuse receptacle is located the outlet or smoke chamber 5 which receives the smoke and non-combustible vapors or gases given off by the refuse during the process of incineration which products are carried off to the outer atmosphere or to a chimney leading to the outer atmosphere by means of a smoke pipe 6 communicating with the top of the outlet chamber.

The wall of the refuse receptacle is preferably constructed in the form of an upright cylinder which terminates at its lower and upper ends, respectively, above the bottom of the ash pit and below the top of the outlet chamber and which preferably comprises two semi-cylindrical or segmental sections 7, 7 which engage each other at their vertical edges by rabbet joints. Around the refuse receptacle is arranged a by-pass, flue or passage 8 which communicates at its lower end with the ash pit and at its upper end with the upper end of the refuse receptacle and the outlet chamber and also communicates with the lower part of the refuse receptacle by means of a plurality of openings 9 formed in the lower part of the refuse receptacle. The outer wall of this by-pass or flue is constructed substantially in the form of an upright cylinder which is composed of

- two semi-cylindrical segments or sections 10, 10 which engage their vertical edges by a rabbet joint and rest at their lower edges on the base 1 while their upper edges engage with the top 11 of the outlet chamber. The vertical joints of the refuse receptacle are preferably in line transversely with the joints between the outer wall sections of the by-pass or flue, and the wall sections of the refuse receptacle are provided at their meeting edges with corresponding pairs of supporting and coupling lugs 12, which project outwardly through openings formed in the meeting edges of the walls of the by-pass, thereby forming a support for the refuse receptacle on the wall of the by-pass. On their outer sides the by-pass wall sections are provided with coupling lugs 13 which are arranged on opposite sides of the supporting lugs of the refuse receptacle, and each pair of refuse receptacle lugs and the companion pair of by-pass wall lugs are connected by a fastening bolt 14 passing through the several lugs on the outer side of the by-pass wall, as shown in Figs. 3 and 4, thereby utilizing the same means for holding the refuse receptacle wall sections and the by-pass wall sections in place and simplifying the construction accordingly.
- 30 The refuse or garbage to be destroyed or consumed is introduced into the upper part of the refuse receptacle through an inlet chute or spout 15 which opens horizontally into the upper part of the refuse receptacle and is provided at its outer end with a lid or door 16 whereby the same may be opened and closed, as shown in Figs. 1 and 4.
- At the lower end of the refuse receptacle is arranged the grate or support for the material which is to be incinerated. As shown in Figs. 3 and 4, this grate comprises an outer grate ring 17 which is capable of being oscillated or shaken by means of an arm 18 projecting laterally from this ring through suitable openings in the apparatus to the exterior thereof where it is accessible for operation by hand. This outer grate ring may be guided in its oscillating movement by any suitable means, for instance, by guideways 19 which are formed on the inner side of the wall of the refuse receptacle and receive the outer edge of the grate ring 17, as shown in Figs. 3, 4 and 5. Within the lower part of the refuse receptacle means are arranged which operate to spread the material thrown into the same and prevent the same from packing so that all parts of the material are exposed to the heating, drying and burning action of the fuel and quick and thorough consumption of the same and reduction thereof to ashes is effected. This spreading means preferably comprises three small lower spreading cones 20 which are arranged side by side in an annular row and each of which tapers upwardly. As shown in Figs. 3 and 4, three of such lower spreading cones are employed but this number may be varied if desired. The outer portions of these lower spreading cones rest upon the outer grate ring 19 and the space between the several lower cones is bridged by the sections 21 of an inner grate ring which are connected with the adjacent lower edges of these lower cones. Each of the lower spreading cones is provided at its upper end with a horizontal outer nozzle 22 projecting with its outer end through an opening in the wall of the refuse receptacle and communicating with the by-pass surrounding the same. The upper end of each lower spreading cone is also provided with an inwardly projecting horizontal nozzle 23 which opens into the interior of the refuse receptacle. Below its nozzles each lower spreading cone is provided with a plurality of perforations 24, as shown in Figs. 3 and 4.
- Above the lower set of spreading cones is arranged a single large upper spreading cone 29 which tapers upwardly and rests with its lower edge on the upper ends of the several small cones and is provided with a plurality of perforations 30. This upper spreading cone is removably seated on the lower cone but is held centrally within the refuse receptacle by means of retaining lugs 31 arranged on the upper ends of the several small lower spreading cones and engaging with the outer side of the upper large cone, as shown in Figs. 3 and 4. Underneath each lower spreading cone is arranged a burner 25 which is adapted to direct the flame upwardly into respective cones. These burners may be supplied with any suitable fuel, such as gas, oil or gasoline by means of a supply pipe 26 arranged on the exterior of the apparatus and connected therewith by branch pipes containing suitable air mixers 27. Upon throwing a batch of garbage or refuse into the refuse receptacle the upper and lower spreading cones operate to break the same up more or less into a loose mass in such manner that it bridges the spaces between the several spreading cones, thereby thoroughly exposing all parts of the refuse to the heating and burning action of the flames and causing the same to be quickly dried and reduced to ashes. The heat of the flames for this purpose passes partly from the burners outwardly through the perforations in the lower cones, partly from the inner nozzles of the lower cones and into the upper cone and outwardly through the openings of the latter and also partly through the outer horizontal nozzles of the lower spreading cones into the by-pass. From the latter the flames and heated air pass inwardly through the openings in the lower part of the refuse receptacle and also over the upper edge of this receptacle into the interior thereof. By this means the mass

of garbage is completely enveloped by the burning gases so that all parts of the same are quickly and thoroughly acted upon by the gases or flames whereby any combustible elements contained in the garbage are vaporized or volatilized into a combustible condition so that they in turn become ignited and aid in the operation of consuming the garbage and reducing the same to ashes.

5 10 Those gases which are generated or developed from the garbage itself while the latter is being dried, heated and burned by the fuel flames are put into combustible condition by the addition thereto of air which 15 is supplied thereto in the upper part of the refuse receptacle above the refuse through the by-pass which latter takes the air from the ash pit and delivers the same into the refuse receptacle at the upper end thereof 20 and also into the central part thereof through the openings in its wall. By thus putting the inflammable gases or vapors which are generated from the refuse or garbage in a combustible condition which aids 25 in the further consumption of the garbage or refuse, the incineration of this material is effected largely by fuel derived from the material itself and thereby effects a considerable saving in the use of other fuel for 30 this purpose so that the consumption of garbage is effected very economically. Any excess flames from the burners which cannot pass freely upward through the spreading cones, grate and garbage will escape 35 from the lower ends of the lower cones and the underside of the grate into the by-pass and be delivered by the latter into the upper part of the refuse receptacle so that back pressure of the flame and possible extinction 40 of the same cannot occur.

In order to prevent the air which passes upwardly through the by-pass from escaping directly through the outlet chamber to the smoke pipe an outer baffle or deflector 45 50 55 60 65 preferably of annular form is arranged to extend from the inner side of the by-pass wall inwardly and downwardly over the upper edge of the refuse receptacle wall, as shown in Fig. 4. By this means the air issuing from the upper end of the by-pass is deflected inwardly and downwardly into the upper part of the refuse receptacle where it becomes mixed with the inflammable vapors of the gases generated by the decomposition of the refuse or garbage and causes the same to be converted into a combustible condition so as to become ignited and add the resulting heat to that of the flames from the burners for promoting rapid disposition of the material.

In order to prevent the vapors generated in the refuse receptacle from passing directly upward through the outlet chamber and out through the smoke pipe a central baffle or deflector 33 preferably of circular

and downwardly dished form is arranged between the upper end of the refuse receptacle and the lower side of the outlet chamber and separated at its outer edge by an annular passage from the outer deflector. 70 This central deflector or baffle is preferably removably supported upon the outer deflector by means of lugs 34 arranged on the marginal portion of said central deflector and resting upon the upper side of the outer 75 deflector, as shown in Fig. 4. As the gases generated from the garbage or refuse rise in the refuse receptacle they are directed laterally by the central deflector where they are intercepted by the inwardly flowing 80 stream of air from the upper end of the by-pass, thereby causing these elements to become mixed and put into combustible condition so that they are consumed and furnish added heat within the refuse receptacle for consuming the contents thereof. By thus thoroughly consuming all the vapors or gases within the incinerator only dead or non-combustible and practically odorless smoke is permitted to escape to the outer atmosphere so that no objectionable results follow from the use of this apparatus.

In order to prevent this incinerator or crematory from unduly heating the space immediately surrounding the same and 95 thereby render its presence in a kitchen unobjectionable, particularly in the summertime, the following means are provided: 35 represents an insulating air jacket formed between the outerside of the wall of the by-pass and an inner intermediate upright wall 36 extending from the base to the top of the outlet chamber. Between this inner intermediate wall and an outer intermediate wall 37 also extending from the base to the top 100 of the outlet chamber is an air circulating 105 chamber or cooling passage 38 which communicates at its lower end through openings 39 in the base with the air space underneath the base, while its upper end communicates with a cooling pipe or flue 40 surrounding the smoke pipe. This cooling pipe 110 communicates with the outer atmosphere or with the chimney into which the smoke pipe leads. The connection between 115 this cooling pipe and the upper end of the cooling chamber 38 is effected by means of a horizontal passage 41 formed in the top of the incinerator and connected at its outer end by openings 60 with the upper end of 120 the flue or passage 38 while its inner end is connected by openings 61 with the lower end of the cooling pipe 40. The passage 41 is heat insulated from the outlet chamber by means of filling 42 of asbestos or similar 125 material. For the purpose of permitting the heated air immediately above the incinerator to enter the air outlet pipe 40 the latter is provided immediately above the top of the incinerator with a plurality of open- 130

ings 43, as shown in Figs. 1 and 4 for this purpose. The radiation of heat from the incinerator to the surrounding space in the room is further reduced or prevented by an insulating air jacket 62 formed between the outer intermediate wall 37 and an outer wall 63, as shown in Figs. 1, 2, 3, 4 and 5.

The main fuel supply pipe contains a valve 44 having a rotatable plug 45 whereby the passage of this valve and the supply pipe may be controlled. This plug is provided with a handle 46 for turning the same. In order to lock this plug in either its opened or its closed position means are provided which preferably comprise an annular row of locking lugs 47 formed on the hub of the handle, and a locking arm 48 pivoted to swing vertically on the adjacent part of the fuel supply pipe and provided at its free end with a notch or jaw 49 adapted to engage with one or the other of the locking lugs 47 of the handle according to whichever one is on the upper side of the valve plug. The valve shown in the drawings is of that type in which the plug is opened or closed by a quarter turn and for that reason the handle of this valve is provided with three locking lugs 47 which are arranged on different quarters. Upon turning the valve plug so that the handle projects downwardly the valve is closed and the plug may be held in this position by engaging the locking arm with the central locking lug, as shown in Figs. 1, 7 and 8. Upon turning the handle vertically in either direction from a pendant position so as to assume a horizontal position the valve plug will be opened and either one or the other of its side lugs 47 will then project upwardly into a position where the same may be engaged by the locking arm for holding the valve plug in its open position.

In order to cause the ash pit door 28 to be opened and closed in unison with the opening and closing of the fuel valve means are provided which preferably comprise a flexible member or chain 50 connected at its lower end with the lower free part of the ash pit door while its upper end is connected with a crank pin 51 arranged on the valve handle 46 eccentrically to the axis thereof and on that side adjacent to the bonnet 52 of the valve casing. By means of this construction the valve handle when turned into a pendant position for closing the fuel valve, as shown in Figs. 1 and 7, will cause the chain to be lowered and the ash pit door to be closed while upon turning the valve handle in either direction into a horizontal position the eccentric or crank pin of the handle will cause the chain to be lifted and the ash pit door to be opened, thereby admitting air into the ash pit at the same time that the fuel is turned on and supplying the increased amount of air

necessary for assisting in the heating, drying and burning of the refuse under treatment.

It will be noted that in this improved refuse incinerator each of the perforated cone-shaped members 20 is arranged in the lower portion of the receptacle and above the grate and that the same is provided with a gas escape tube communicating with a flue which is arranged adjacent to the side of the receptacle and has communication therewith at the side thereof, and that means are provided for supplying gas to each of said perforated cone-shaped members.

This incinerator or crematory is comparatively simple and inexpensive in construction, the same has no parts which are liable to get out of order, the same can be filled with garbage or refuse without liability of clogging the machine or producing an incomplete decomposition of the same and it permits of disposing of such material at comparatively low cost and without producing any discomfort or unpleasantness.

I claim as my invention:

1. A refuse incinerator comprising a refuse receptacle, a plurality of perforated spreading cones arranged in the lower part of said receptacle, a burner arranged below each of said cones, and a grate comprising an outer ring mounted on the lower part of said receptacle and supporting said cones and an inner ring connecting the several cones independently of said outer ring.

2. A refuse incinerator comprising a refuse receptacle, an ash pit arranged below the refuse receptacle, a flue arranged adjacent to the outer side of said receptacle and communicating at its lower end with said ash pit, a perforated spreading cone arranged in said receptacle and provided at its upper end with a horizontal nozzle which opens into said flue, and a burner arranged below said cone.

3. A refuse incinerator comprising a refuse receptacle, an ash pit arranged below the refuse receptacle, a flue arranged adjacent to the outer side of said receptacle and communicating at its lower end with said ash pit, a perforated spreading cone arranged in said receptacle and provided at its upper end with an outwardly projecting nozzle which opens into said flue and an inwardly projecting nozzle which opens into said receptacle, and a burner arranged below said cone.

4. A refuse incinerator comprising a refuse receptacle, an ash pit arranged below the refuse receptacle, a flue arranged adjacent to the outer side of said receptacle and communicating at its lower end with said ash pit, a perforated spreading cone arranged in said receptacle and provided at its upper end with an outwardly projecting

nozzle which opens into said flue and an inwardly projecting nozzle which opens into said receptacle and is provided below said nozzles with perforations, and a burner 5 arranged below said cone.

5. A refuse incinerator comprising a refuse receptacle, a plurality of lower perforated spreading cones arranged side by side in said receptacle, an upper perforated 10 spreading cone mounted on said lower spreading cones, and burners arranged below said lower spreading cones.

6. A refuse incinerator comprising a refuse receptacle having a perforated wall, 15 an ash pit arranged below said receptacle, perforated cones arranged in said receptacle, burners arranged below said cones, an upright flue surrounding said receptacle and communicating at its lower end with said 20 ash pit, an outlet chamber communicating with the upper ends of said receptacle and said flue, and an outer deflector projecting from the wall of said outlet chamber inwardly over the upper end of the wall of 25 said receptacle.

7. A refuse incinerator comprising a refuse receptacle having a perforated wall, an ash pit arranged below said receptacle, perforated cones arranged in said receptacle, 30 burners arranged below said cones, an upright flue surrounding said receptacle and communicating at its lower end with said ash pit, an outlet chamber communicating with the upper end of said receptacle and 35 said flue, an outer deflector projecting from the wall of said outlet chamber inwardly over the upper end of the wall of said receptacle and an inner deflector arranged between the upper end of said receptacle and 40 the lower end of said outlet chamber and projecting outwardly over said outer deflector.

8. A refuse incinerator comprising a refuse receptacle having a perforated wall, 45 an ash pit arranged below said receptacle, perforated cones arranged in said receptacle, burners arranged below said cones, an upright flue surrounding said receptacle and communicating at its lower end with said 50 ash pit, an outlet chamber communicating with the upper ends of said receptacle and said flue, an outer deflector projecting from the wall of said outlet chamber inwardly

over the upper end of the wall of said receptacle, and an inner downwardly dished 55 deflector arranged between the upper end of said receptacle and the lower end of said outlet chamber and projecting outwardly over said outer deflector.

9. A refuse incinerator comprising a 60 refuse receptacle constructed of segmental sections which are provided at their meeting edges with outwardly projecting lugs, a shell surrounding said receptacle to form a flue between the same and constructed of 65 segmental sections and provided at their meeting edges with openings which receive the lugs of said receptacle and with laterally projecting lugs which register with the lugs of said receptacle, and means for connecting 70 the lugs of said shell and receptacle outside of said shell.

10. A refuse incinerator comprising a refuse receptacle, a burner arranged below said receptacle, and provided with a fuel 75 supply pipe, a valve arranged in said pipe for controlling the fuel passage and having a rotatable plug and handle connected with said plug, an ash pit arranged below the refuse receptacle and burners and having 80 an opening, a door pivotally mounted on the ash pit and controlling said opening thereof, and means for causing said door and valve to open and close simultaneously upon operating said valve comprising a flexible 85 member connected at one end with said door and at its other end with said handle on one side of said plug and adjacent to the bonnet of said valve.

11. A refuse incinerator comprising a 90 refuse receptacle, a flue adjacent to the side of the receptacle and having communication therewith at the side thereof, a grate, a perforated cone-shaped member in the lower portion of the receptacle and above the 95 grate and provided with a gas escape tube communicating with said flue, and means for supplying gas to said perforated cone-shaped member.

Witness my hand this 21st day of March, 100 1914.

EDWARD KENER, JR.
